UNITED STATES PATENT OFFICE.

JOSEPH LIPKOWSKI, OF PARIS, FRANCE, ASSIGNOR TO SOCIÉTÉ GENERALE DES FREINS LIPKOWSKI, OF PARIS, FRANCE.

AIR-BRAKE.

SPECIFICATION forming part of Letters Patent No. 727,394, dated May 5, 1903.

Application filed January 31, 1903. Serial No. 141,316. (No model.)

To all whom it may concern:

Be it known that I, JOSEPH LIPKOWSKI, a subject of the Emperor of Russia, and a resident of Paris, France, have invented Improvements in Air-Brakes, of which the following is a specification.

This invention relates to air-brake cylinders operating on the general principle described in my United States Patent No. 549,800—that is, a brake-cylinder in which two distinct movements of the brake-rod and piston are produced for one power application of the brakes.

The main object of this invention is to improve the construction of such a brake-cylinder and to increase the capacity of the auxiliary reservoir without unduly increasing its bulk.

In the accompanying drawings, Figure 1 is a side elevation of my improved brake-cylinder. Fig. 2 is a sectional view on the line 2 2, Fig. 5. Fig. 3 is a cross-sectional view on the line 3 3, Fig. 1. Fig. 4 is a plan view, partly broken away. Fig. 5 is an end view, and Fig. 6 is a detail of a port.

The brake-cylinder 1 and reducer-cylinder 2 are preferably formed in one casting, while the auxiliary cylinder 3 is bolted to the open end of the brake-cylinder. A check-valve 5 chamber and various ports are cast in the metal of the brake and reducer cylinders, while a plate 5 near the end of the reducer has three openings 6, 7, and 8. Opening 6 passes to above the check-valve 4 and from there to the rear end of the brake-cylinder, and opening 8 leads direct to the reducer-cylinder, while opening 7 leads to below the check-valve 4 and from there to the forward end of the brake-cylinder. A piston-rod 9 passes through a suitable stuffing-box 10 in the end of the reducer-cylinder and carries a small piston 11 within the reducer-cylinder and a large piston 12 within the brake-cylinder. The piston 12 has an extending tubular trunk 13, fitting against a piston-packing 14 against the piston 11, while a conical tube 15 bears against the packing-ring 16 of the large piston 12. The smaller end of this conical tube fits over the piston-rod 9 and is held in position against the piston-face by a spring 17 and nuts 18 on the rod. An annular

bearing-piece 19 is clamped between the brake-cylinder 1 and the reservoir 3 to serve as a rest for the spring 20, which bears at its other end against the cross-head 21 on the 55 end of the piston-rod. A barrel-guide 22 may be inserted between the bearing-piece to prevent any undue sag of the spring 20, this barrel-guide being secured on the piston-rod between the nuts 18 and the spring 17. Opening 23 in the trunk 13 and opening 24 in the tube 15 open communication between the reservoir 1 and such trunk, and thus the trunk and tube serve to augment the capacity of the reservoir by using part of the area of the 65 brake-cylinder as an auxiliary storage-cell for the auxiliary reservoir.

An air-distributer X, corresponding to a triple valve, is controlled by varying pressure in the train-pipe and is so operated upon 70 a slight reduction therein as to automatically open the reducer-cylinder 2 to the atmosphere, which causes the brake-shoes to be moved into light contact with the wheels with a force equal to the area of the small piston times the pressure in the auxiliary reservoir 3. On the forward movement of the piston 12 the air in front of it passes out through port 7, up through the check-valve 4, and through port 6 to occupy a position at 75 the right of the piston 12. When in this position, it will be seen that no expansion of the reservoir-air has taken place, as there has been free intercommunication between the reservoir 3 and cylinder 1. Upon a further reduction of train-pipe pressure the distributor X so acts as to more or less reduce the pressure in the brake-cylinder 2, whereupon the brakes will be applied with a force equal to the entire area of the large piston 90 times the difference in pressure between the auxiliary-reservoir pressure and the cylinder-pressure.

I claim as my invention—

1. A piston-rod for an air-brake cylinder 95 carrying a large and a small piston, a tubular trunk between them and an opening from said trunk through the larger piston, substantially as described.

2. An air-brake auxiliary reservoir, a brake-cylinder and a reducer, in combination with a piston-rod, a small and a large piston there-

on, and a tubular trunk in the brake-cylinder opening into the auxiliary reservoir, substantially as described.

3. An air-brake, comprising a reducer, a 5 brake-cylinder and an auxiliary reservoir, a brake-rod therein, two pistons therein, one of larger diameter than the other, the smaller piston in the reducer-cylinder and the larger in the brake-cylinder, a tubular trunk between the two pistons and an opening from 10 said trunk to the auxiliary reservoir, substantially as described.

4. An air-brake auxiliary reservoir and 15 brake-cylinder in combination with a piston in the cylinder, said piston carrying a tubular trunk communicating with the reservoir, and means for preventing the expansion of pressure on the reservoir side of the piston during part of its travel, substantially as 20 described.

5. An air-brake auxiliary reservoir and 25 brake-cylinder, in combination with a piston in the cylinder, the reservoir being secured to but open to the cylinder at one end, a tubular trunk extending into the cylinder and connecting with the reservoir, substantially as described.

6. A piston-rod for an air-brake cylinder 30 having a small piston, a large piston, a tubular trunk between them, packing-rings for each piston, a conical tube fitting against the packing-ring of the large piston and a spring

between said sleeve and piston-rod, substantially as described.

7. A piston-rod for an air-brake cylinder 35 having a small piston and a large piston, the large piston having a tubular trunk, a conical tube adapted to fit against the large-piston face, the smaller end of the tube fitting over the piston-rod, and a spring means for 40 holding said conical tube against the piston-face, substantially as described.

8. In combination with a brake-cylinder 45 and an auxiliary reservoir, a fixed annular bearing-piece, a piston and rod, a cross-head at the end of the rod in the main chamber, a spring between the bearing-piece and rod, and a guide-barrel between the cross-head and bearing-piece carried by the rod, substantially as described.

9. An air-brake cylinder and an auxiliary reservoir secured thereto, in combination with a piston-rod, a piston in the brake-cylinder and a tubular trunk carried on the piston-rod within the brake-cylinder, and an 50 opening from the trunk to the auxiliary reservoir, substantially as described.

In testimony whereof I have signed my name to this specification in the presence of two subscribing witnesses.

JOSEPH LIPKOWSKI.
